UNITED STATES PATENT OFFICE.

CHARLES SONNEBORN, OF WEST PITTSBURGH, PENNSYLVANIA, ASSIGNOR TO PRESSED METAL RADIATOR COMPANY, OF PITTSBURGH, PENNSYLVANIA, A CORPORATION OF PENNSYLVANIA.

HEAT-RADIATOR.

1,226,129.

Specification of Letters Patent.

Patented May 15, 1917.

Application filed January 22, 1916. Serial No. 73,763.

To all whom it may concern:

Be it known that I, CHARLES SONNEBORN, a resident of West Pittsburgh, in the county of Allegheny and State of Pennsylvania, have invented a new and useful Improvement in Heat-Radiators, of which the following is a specification.

This invention relates to heat radiators, and more particularly to heat radiators designed for use as transformer coolers.

The coils of large electrical transformers are usually immersed in a bath of oil to prevent short circuits and by radiating to the atmosphere the heat generated in the transformer, to also protect the coils from injury. The object of this invention is to provide a cheap and efficient form of cooler, one which can compete with prior coolers built up of ordinary pipe and pipe fittings or other prior devices; one which is of light weight, is entirely leakproof and has a lesser number of joints or connections than prior coolers of this class; one which can be readily built up to any desired size or amount of radiating surface; and one which can be operated with a proportionately small quantity of oil bath and is constructed to provide a large exposed surface area with thin columns of liquid so that the heat of the oil is quickly, thoroughly and efficiently radiated to the air.

Further objects of the invention are in part obvious and in part will appear more in detail hereinafter.

The invention comprises the construction and arrangement of parts hereinafter described and claimed.

In the drawings, Figure 1 represents a sectional elevation of one form of cooler embodying the invention; Fig. 2 is a plan view thereof; Fig. 3 is an enlarged elevation partly in section of one of the radiator members; Fig. 4 is a detail end view from the left in Fig. 3; Fig. 5 is a cross section on the line 5—5, Fig. 4; and Fig. 6 is a detail sectional view on the line 6—6, Fig. 4.

The cooler shown in the drawings comprises a tank or reservoir 1 containing the oil bath, which is maintained at a level indicated by the dotted line A—A. This tank is provided with a ledge or series of projections 2 near its upper end serving as supports for the primary and secondary coils of a transformer shown by dotted lines at

3 and which is provided with projections 4 resting upon the projections 3 to support the coils immersed in the oil bath.

The heat generated by the coils is transmitted to the atmosphere by circulating the oil bath through a series of radiators 5, 60 which are of special form and construction, enabling them to be made and assembled with the tank at low cost, and which also are of light weight, have maximum efficiency and are substantially leakproof. 65

The reservoir 1 is provided near its top and bottom with two series of openings 6 arranged in pairs vertically aligned, one of said radiators communicating at its header ends with the aligned openings of a pair. 70

Each radiator comprises one or more units or sections each of which consists of one or a plurality of hollow header sections 7 and a plurality of comparatively thin walled rolled or drawn metal tubes 8 communicating therewith. The header sections may be of various forms, depending upon circumstances, such as the size of the tank or reservoir and the number of tubes and amount of exposed radiating surface desired. Each 80 header section shown is of hollow cast metal with a central portion 9 having threaded openings 10 in its opposite faces, and laterally extending wings 11, the cavities in which communicate with the openings 10. 85 On one side of the header section its wall 12 slopes off in both directions to the ends of the wings 11, while the opposite side is straight from end to end, being broken by the shallow transverse grooves 13 between 90 adjacent hollow bosses 14 spaced thereon.

The header sections may be made of any suitable metal, preferably malleable iron castings, although castings of alloys, aluminum, brass, bronze or ordinary cast iron are 95 suitable. Malleable iron is preferable due to its low cost, its homogeneous composition and texture and its usual freedom from blowholes. The header sections are made as light as possible with due regard for 100 strength.

Any number of hollow bosses 14 may be provided on each header section, so as to enable the radiator unit to include any desired number of tubes 8. The openings in 105 the hollow bosses 14 and the tubes 8 are of flattened or of oval or other thin oblong form to secure a large exposed surface area

and to also give a minimum diameter of the liquid column in the tube so that the center of the column is nearer to the air than in a round or other form of tube. The ends of the tubes are cut off square and are secured to the header sections preferably by welding or brazing so as to secure a perfect seal and guard against leakage or loss of oil.

For the tubes any thin wrought metal pipe which is of light weight and is impervious to oily liquid is suitable. Said pipes may be made of any metal, for example, copper, bronze or the like, but preferably are formed of wrought iron and may be commercially rolled or drawn tubing, seamed or seamless and of flattened or oval or of oblong form, as before described.

As stated, any number of tubes 8 may be used to connect the two header sections of a given radiator unit, so that only one tube may be used if desired, although the drawings, for purposes of illustration, show three tubes connecting each pair of header sections. Said three tubes are shown as in the same plane, but the number may be increased by including more tubes in the same plane, or by locating the tubes connecting header sections in parallel rows of say two, three or more each. Furthermore, with any form of radiator unit, the radiator may be built up to any desired size, thereby providing for any amount of exposed radiating surface. This is accomplished by connecting a series of radiator units or sections to each other to form one of the radiators, the drawings showing four sections or units in each radiator. The several units or sections are connected by right and left-hand threaded nipples 16, which are threaded into the opening 10 of the header sections, the joints being made tight, if desired, by a lead or other soft metal washer 17 inserted between radiator sections. The outer section or unit of the radiator has its outer holes 10 closed by suitable plugs 18, which may be removed in case the joints between radiator sections leak to enable them to be tightened up by a tool inserted through the holes 10. Each radiator is connected to the tank or reservoir 1 by right and left-hand nipples 19 threaded into the openings 10 of the inner radiator unit or section and into an opening 6 of the tank or reservoir, which, for this purpose, is provided with flanged fitting 20 to receive said nipple, and which fitting is welded or brazed to the tank wall around said opening. Preferably, also, the threaded connections at both ends of the

nipples 19 will be closed or sealed by welding or brazing after assemblage to insure tight joints and prevent leakage.

While the invention has been shown applied for use as a transformer cooler it is to be understood that it is not so restricted but is capable of other uses. For example, the tank or reservoir with the radiator sections applied thereto may be used for holding and cooling oil baths for quenching metals during heat treatment or for cooling other substances than oil.

The radiators, formed of one or more sections or units as described, are spaced around the periphery of the oil reservoir, as shown in Fig. 2. The thin walled tubes largely increase the ability to quickly transmit the heat and so reduce the cross section of the liquid columns as to largely increase the efficiency. The joints are all tight and the construction is not only strong but also entirely prevents loss of oil by leakage. This form of radiator enables a very large exposed surface area to be secured with a minimum volume of liquid in the tank so that the first cost of installation of the tank, radiator and oil bath is a minimum. The cost of upkeep is also low due to the tight joints and the high efficiency.

What I claim is:—

1. A heat radiator, comprising a tank or reservoir for containing a liquid, and a series of built-up radiators spaced around the periphery thereof, each of said radiators comprising a plurality of header sections having a central portion provided with openings and two wings, metal tubes secured to the edges of openings in said wings and connecting the header sections, and nipples threaded into the central openings in said header sections and connected to the reservoir.

2. A heat radiator, comprising a tank or reservoir for containing a liquid and provided with two series of openings near its top and bottom, and a series of radiators spaced around said tank, each radiator comprising a plurality of units each embodying hollow metal sections and a plurality of metal tubes welded or brazed thereto, internal connections for the units of said radiators, and nipples connecting said radiators to the tank.

In testimony whereof, I have hereunto set my hand.

CHARLES SONNEBORN.
